UNITED STATES PATENT OFFICE.

STEFAN WOJCIK, OF DETROIT, MICHIGAN, ASSIGNOR OF ONE-HALF TO JACOB LEWANDOWSKI, OF DETROIT, MICHIGAN.

CUE-TIP CLAMP.

1,381,386.

Specification of Letters Patent. Patented June 14, 1921.

Application filed November 30, 1920. Serial No. 427,434.

To all whom it may concern:

Be it known that I, STEFAN WOJCIK, a citizen of Poland, residing at Detroit, in the county of Wayne and State of Michigan, have invented certain new and useful Improvements in Cue-Tip Clamps, of which the following is a specification.

This invention relates to certain new and useful improvements in cue tip clamps and has particular reference to a clamp having a resiliency mounted head and adapted to engage a cue tip in axial alinement with the cue stick for holding the same in proper position during the cementing operation.

With the above and other objects in view that will appear as the nature of the invention is better understood, the same consists in the novel form, combination and arrangement of parts hereinafter more fully described, shown in the accompanying drawing and claimed.

In the drawing, wherein like reference characters indicate corresponding parts throughout the several views,

Figure 1 is a side elevational view, partly in section of the outer end of a cue stick and cue tip clamp in operative position thereon,

Fig. 2 is a top plan view of the clamp, Fig. 3 is a side elevational view of the outer end of the cue stick and clamp shown in Fig. 1,

Fig. 4 is a horizontal sectional view taken on line IV—IV of Fig. 1, and

Fig. 5 is a horizontal sectional view taken on line V—V of Fig. 1.

Referring more in detail to the accompanying drawing, there is illustrated a cue stick 1 having a rubber or leather tip 2 secured to the outer end thereof.

The clamp provided for holding the tip 2 in intimate contact with the stick 1 during cementing operation embodies a longitudinally split tubular clamp body 3 carrying a collar 4 adjacent the inner end thereof provided with opposed ears 5 through which a tightening screw 6 is threaded for holding the tubular clamp 3 in position on the stick 1. The opposite sides of the tubular clamp body 3 carry laterally projecting apertured lugs 7 adjacent the outer end thereof through which lugs the rods 8 are slidably mounted. A coil spring 9 surrounds each rod inwardly of the lugs 7, the springs at

their outer ends engaging the lugs and confined at their inner ends by plates 10 carried by said rods, the inner faces of the plates being curved as at 11 coincident to the curvature of the tubular clamp 3, thereby holding the rods against rotation and permitting free sliding movement thereof. A head 12 carrying a finger ring 13 is provided with a concaved plate 14 having lateral ears 15 to which the outer ends of the rods 8 are secured.

In the operation of the device, the tubular clamp 3 is secured in the desired position on the cue stick 1 by the clamping screw 6. The head 12 is moved outwardly by gripping the finger ring 13 to provide sufficient space between the concaved plate 14 and the outer end of the cue stick for correctly positioning the cue tip 2 on the stick, the adjacent faces of the stick and cue being supplied with green glue or other cementitious material. The concaved plate 14 carrying the rods 8 being moved outwardly against the tension of the springs 9, release of pulling pressure on the head 12 will cause the arms 8 to move inwardly under influence of the springs 9 with the concaved plate 14 pressing the cue tip 2 into intimate engagement with the end of the cue stick. The stick and clamp are allowed to remain in this position until the cementing material is thoroughly dried, at which time the release of the tightening screw 6 will permit the clamp to be removed from the stick with the outer end of the stick and tip finished in the usual manner.

While there is herein shown and described the preferred embodiment of the present invention, it is nevertheless to be understood that minor changes may be made therein without departing from the spirit and scope of the invention as claimed.

What is claimed as new is:—

1. A cue tip clamp of the type described comprising a tubular clamping body, a clamp screw carried by the inner end thereof, opposite apertured lugs carried by the tubular clamping body adjacent the outer end, tensioned rods slidably mounted in the apertured lugs, and a cue tip pressing plate carried by the outer ends of said rods.

2. A cue tip clamp of the type described comprising a tubular clamping body, a clamping screw carried by the inner end

thereof, oppositely disposed apertured lugs carried by the outer end of said clamping body, a rod slidably mounted in each lug, a plate carried by the inner end of each rod having the edge thereof adjacent the clamping body curved coincident thereto preventing rotation of the rods, compression springs

surrounding the rods between the apertured lugs and plates, and a concaved plate carried by the outer ends of said rods and overlying the open outer end of said clamp. 10

In testimony whereof I affix my signature.

STEFAN WOJCIK.
